UNITED STATES PATENT OFFICE.

OSCAR GREENBAUM, OF NEW YORK, N. Y., ASSIGNOR TO RAUDNITZ
AND POLLITZ, OF NEW YORK, N. Y., A FIRM.

BAG OR THE LIKE.

SPECIFICATION forming part of Letters Patent No. 786,804, dated April 11, 1905.

Application filed January 18, 1905. Serial No. 241,634.

To all whom it may concern:

Be it known that I, OSCAR GREENBAUM, a citizen of the United States, residing in New York city, borough of Manhattan, New York, 5 have invented certain new and useful Improvements in Bags or the Like, of which the following is a specification.

My invention relates to improvements in the class of bags, pocket-books, and the like 10 which are provided with a frame secured along the mouth of a pocket and having knobs adapted to coact in holding the frame and pocket closed; and the object of my invention is to provide improved means for holding the outer 15 sides of the bag closed to prevent the loss of the contents.

In one form of my invention I provide a bag, pocket-book, or the like having side pockets and an intermediate pocket provided with 20 a frame secured at the mouth of the pocket and having fastening devices to coact in holding the frame closed, with a tab or strap secured to one wall adapted to fold over the mouth of the bag, and provided with an opening 25 to pass over or receive the fasteners on the frame and with complemental fastening means on the tab and an outer wall of the bag or pocket-book for holding the tab when folded over the mouth of the bag.

Reference is to be had to the accompanying drawings, forming part hereof, wherein—

Figure 1 is a side view of a bag provided with my improvements, and Fig. 2 is a perspective view of the same shown open.

Similar letters of reference indicate corresponding parts in the views.

As shown in the drawings, the bag A is provided with side pockets B C and with an intermediate pocket D, which may be constructed in any well-known manner.

At E is a frame secured along the edges or mouth of pocket D, said frame having fastening devices F, shown in the form of knobs, adapted to coact in holding the pocket D and frame E closed in well-known manner.

At G is indicated a tab or strap, secured at one end to the wall A², as by stitches a, or in any other suitable manner, which tab or strap is adapted to fold over the edge of the bag and

to be attached to the wall A³. To secure the 50 free end of the tab to the wall A³, I have shown complemental fasteners b b², such as the well-known glove-fasteners, attached, respectively, to the tab G and to the wall A³. The tab G is provided with an opening G², that permits the 55 projecting knobs F to pass through the tab, so that the tab may fold down snugly over the edges of the walls of the bag or pocket-book without interference by the knobs F, thereby holding the walls A² A³ and the entire bag securely closed. The tab G may be made in the form of a fork, having the two prongs secured to the wall A², providing the opening G², as indicated in Fig. 2, whereby the end portion G³ may carry the fasteners b and be free for 60 operation.

Having now described my invention, what I claim is—

1. A bag or the like provided with a pocket having a frame at its mouth, said frame having fastening means for keeping it closed, a tab secured to one wall of the bag and provided with an opening to receive said fastening means, and means for detachably connecting said tab with a wall of the bag, substantially as described. 70

2. A bag or the like provided with side pockets and an intermediate pocket, a frame secured along the edges of the intermediate pocket and provided with fastening means, a tab secured to a wall of the bag and adapted to fold over the mouths of the pockets, said tab being provided with an opening to receive the fastening means on the frame and coacting fastening means carried by the tab and an opposite wall of the bag, substantially as described. 75

3. A bag or the like provided with side pockets and an intermediate pocket, a frame secured along the edges of the intermediate pocket and provided with fastening means, a tab having a fork-like portion providing an opening to pass over the fastening means on the frame, the prongs of the tab being secured to a wall of the bag, and complemental fastening means respectively carried by the tab and by a wall of the pocket, whereby the tab may fold over the open mouths of the pockets and 90

receive the fasteners on the frame through the opening, substantially as described.

4. A bag or the like provided with side pockets and an intermediate pocket, a frame secured along the edges of the intermediate pocket and provided with coacting knobs, a tab secured to a wall of the bag and provided with an opening to receive said knobs, and complemental fastening devices secured re-

spectively to the tab beyond its opening and to a wall of the bag, whereby when the tab is folded over the open mouths of the pockets the knobs will pass through the opening in the tab, substantially as described.

OSCAR GREENBAUM.
